Primary Examiner — Jeffrey D Asch*Assistant Examiner* — Tracey J Bell(74) Attorney, Agent, or Firm — Eric Kelly(57) CLAIM

What is claimed is the ornamental design for an ornament, as shown and described herein.

DESCRIPTION

FIG. 1 illustrates a front, top, and right-side perspective view of an ornament, showing our new design;

FIG. 2 illustrates a back, top, and left-side perspective view thereof;

FIG. 3 illustrates a top view thereof;

FIG. 4 illustrates a front view thereof;

FIG. 5 illustrates a bottom view thereof;

FIG. 6 illustrates a right-side view thereof (note, a left-side view although not depicted is a mirror image of the depicted right-side view except for the exact placement of the jewels); and,

FIG. 7 illustrates a back view thereof.

The broken lines in the figures depict portions of the ornament that form no part of the claimed design.
